BEARING DEVICE FOR PENKNIVES

Filed July 22, 1925

Charles W. Guttzeit INVENTOR.

BY *C. M. Clark*
ATTORNEY.

UNITED STATES PATENT OFFICE

CHARLES W. GUTTZEIT, OF NEW YORK, N. Y.

BEARING DEVICE FOR PENKNIVES

Application filed July 22, 1925. Serial No. 45,259.

My invention relates to an improvement in a bearing insert for opposing the wear between a spring and a movable coacting member, whereby to overcome the destructive or 5 wearing action of one against the other.

The invention is particularly applicable to use with pen knives or similar devices in which a movable blade or other element is opened or closed, or moved from one position 10 to another, under the holding or friction exerting action of a spring, to maintain the blade in any desired position.

In the accompanying drawings showing one adaptation of the invention:

15 Figure 1 is the longitudinal sectional view of a pen knife, utilizing the invention.

Figure 2 is a partial similar view showing the blade adjusted to a different position.

20 Figure 3 is a detailed view of one end of the spring, showing the bearing insert.

Figure 4 is a cross section on the line IV—IV of Fig. 3.

25 Figure 5 is a detail view of the insert, detached.

Figure 6 is a view showing a modified construction providing for application of the insert to the blade.

As is well understood, the friction of one 30 metal against another of the same physical characteristics or similar as to hardness etc., is rapidly destructive of the wearing faces. For such reason, it is desirable to oppose a metal of any particular wearing value, hardness, or temper, with a resisting metal acting 35 as a bearing, of different physical characteristics.

This is particularly true in connection with the manufacture of knives, cutlery, or the like, made of stainless steel. In such cases 40 great difficulty is usually experienced, because of the wearing and grinding effect on the steel at the point or area where the surface of the spring of a pen knife for instance, comes into contact with the blade member. Where the 45 knife blade is made of all plain carbon steel, such wearing and grinding effect is not especially noticeable, but when both the spring and the blade are made of stainless steel, it has heretofore been found impossible 50 to eliminate the wearing and grinding ac-

tion, where the contacting surfaces of the blade and spring are respectively of such material.

In the manufacture of cutlery, stainless steel is particularly desirable. I overcome 55 the suggested difficulty or objection by interposing between the relatively movable and stationary member, as the blade and the spring, an insert of a bearing material having different physical characteristics from that 60 of the element against which it bears.

In the drawings, showing the application of the invention to an ordinary pocket knife, the blade 2 is pivoted at 3 in the usual way between the sides 4 of the handle, between 65 which at one side is the usual holding spring 5, held by one or more rivets 6.

The hinged end of the blade 2 is of usual standard construction adapting it to be held in an erected or closed position by the action 70 of the spring 5, bearing against the end corner or upper or side edge of the hinged portion of the blade as will be readily understood. For the purpose of overcoming the undesirable friction and resulting wear, I insert in the 75 bearing face of spring 5, a separate bearing piece 7, of suitable material adapted to best oppose the constant wear with the blade member. As shown, such insert is of dovetail form, inserted in a corresponding receiving 80 socket in the blade as shown, and extending across from one side to the other of the spring.

Conversely, the insert 7 may be in the same way, placed in the end or adjacent edge portion of the blade, as in Fig. 6, so that with 85 either construction, there is always present, a bearing contact between the metals of different physical characteristics.

The invention may, of course, be applied to a single blade knife at one end only, or at 90 both ends, in the case of a two or plural blade construction.

The particular material of which the insert is made is immaterial, so long as it provides the desirable condition of opposing against 95 the steel blade, or a blade of so-called stainless steel, an inserted bearing member of a different kind.

Thus, the insert may be made of hard manganese bronze, or a piece of "glass hard" stain- 100

less steel of very much greater hardness than that of the blade itself, or a piece of quartz, etc. When the bearing insert is located in the blade, it makes contact with the comparatively softer spring 5, so that the desired conditions in either case are present.

It will be understood that the shape, size, proportions or other details of the insert, or the knife, or other article with which it is embodied, may be variously changed or modified by the skilled mechanic, to adapt the invention to various conditions of use; but that all such changes, are to be understood as within the scope of the following claims.

15 What I claim is:

1. A pocket knife blade, a tang on one end of said blade having a pivotal supporting portion on said tang, in combination with a bearing portion on the extremity of said tang, said bearing portion comprising bearing metal, both said tang and bearing portion having lugs on their adjoining edges, the lugs on the bearing portion and the lugs on the tang having interlocking engagement, respectively, with each other, said tang and bearing portion being substantially co-extensive as to width and thickness.

2. A steel pocket knife blade, a tang on one end of said blade having a pivotal supporting means on said tang, in combination with a bearing portion on the extremity of said tang, said bearing portion comprising bearing metal, the bearing portion being fixedly secured to the extremity of the tang, the adjoining exterior edges and sides of said tang and bearing portion being substantially co-planar.

In testimony whereof I hereunto affix my signature.

CHARLES W. GUTTZEIT.
